UNITED STATES PATENT OFFICE.

OTTIS E. HARDESTY, OF SHERIDAN, WYOMING.

COLLAPSIBLE SHIPPING CASE.

Application filed May 12, 1924. Serial No. 712,820.

To all whom it may concern:

Be it known that I, OTTIS E. HARDESTY, a citizen of the United States of America, residing at Sheridan, in the county of Sheridan and State of Wyoming, have invented certain new and useful Improvements in Collapsible Shipping Cases; and I do hereby declare that the following is a full, clear, concise, and exact description of the invention, such as will enable others skilled in the art to which it appertains to make and use the same.

This invention relates to improvements in foldable or collapsible shipping cases, having for an object to provide a shipping case particularly advantageous for the safe shipping of small live stock, such for example, as poultry, pigs, sheep, et cetera, which when not in use, may be folded or collapsed and thereby require but a minimum amount of space, hence reducing the shipping costs of the case, as well as rendering it possible to more readily handle the same when empty.

It is also an object of the invention to provide a shipping case of the character mentioned having the sides, top, and bottom thereof so closed as to prevent the stock housed therein from extending their legs, heads, or other parts through the same, and becoming broken or severed.

Yet another object of the invention is to provide a foldable shipping case having means upon the ends, sides, and top sections thereof adapted to be interengaged in order that the same will be held relatively rigid and immovable, hence ensuring that stability necessary to such devices, which during shipping, are subjected to exceedingly rough usage.

Other objects of the invention will be in part obvious, and in part pointed out hereinafter.

In order that the invention and its mode of application may be readily understood by persons skilled in the art, I have in the accompanying illustrative drawings, and in the detailed following description based thereupon, set out one possible embodiment 50 of the same.

In these drawings:—

Figure 1 is a perspective view of the improved shipping case in set-up position;

Figure 2 is a vertical longitudinal section 55 through the same, taken on the line 2—2 of

Figure 1 looking in the direction in which the arrows point;

Figure 3 is a vertical transverse section taken on the line 3—3 of Figure 2 looking in the direction in which the arrows point; 60

Figure 4 is a perspective view of the shipping case in its partially folded or collapsed position;

Figure 5 is a similar view showing the case in its fully folded or collapsed position; 65

Figure 6 is a detail in perspective of the intermediate partition of the shipping case; and,

Figure 7 is an enlarged fragmentary detail section taken on the line 7—7, looking 70 in the direction in which the arrows point.

Having more particular reference to the drawings, in connection with which like characters of reference will designate corresponding parts throughout, the improved shipping case may be stated to comprise a sheet metal or similar bottom 1 having the side portions thereof upturned or flanged as indicated at 2 and provided with sleeves adapted to receive similar sleeves formed 80 upon the adjacent marginal portions of side sections 3 therebetween, whereupon pivots or pintles 4 are passed through the aligned sleeves and obviously, serve to pivotally connect said side sections 3 to the flanged 85 up-standing portions 2 of said bottom 1. In this connection, it will be noted that the opposite side portions of the side sections 3 are provided with other sleeves adapted to receive therebetween sleeves formed upon 90 the adjacent marginal portions of top sections 5, whereupon pivot pins 6 are passed through the aligned sleeves, thus serving to hingedly or pivotally connect the several top sections 5 of the improved shipping case 95 to the side sections indicated herein by the numeral 3.

End sections or walls having inclined opposite sides and indicated by the numeral 7 are provided the shipping case and are 100 hingedly connected, as indicated at 8, to the opposite end portions of the sheet metal bottom 1 in the manner clearly shown in the Figures 2 and 3.

The side, top and end sections 3, 5 and 7, 105 as will be noted upon reference to the drawings are reticulated. That is, these various sections consist of frames covered with a wire mesh or similar material of the desired gauge or size. Thus, the securing of proper 110

ventilation through the shipping case is ensured and at the same time, the gauge of the mesh material covering the frames of such sections 3, 5 and 7 is such as will positively prevent the live stock contained therein from extending their legs, heads, or other parts through the same, followed by possible breaking or severance of the same.

In order that positive connection will be established as between the sides and ends 3 and 7 of the improved shipping case, I may and preferably do secure to the inner sides of the opposite end portions of said sections 3, channeled ribs 9 which are of widths and depths sufficient to permit of their positive engagement over adjacent portions of the inclined sides of said end sections 7, in the manner as clearly shown in the Figures 1 and 3. By reason of this interengagement or connection between the sections 3 and 7, it will be understood that the case will have that stability necessary to permit the same to successfully withstand rough usage imparted thereto. Also, the possibility of undue movement as between the sections 3 and 7 will be positively eliminated.

In order that the shipping case may be divided into several compartments, if desired, an intermediate wall or partition section indicated by the numeral 10 is provided, this section being constructed and formed in a manner corresponding to the sections 7 and having hinged connection as indicated at 11 to the upper side of the intermediate portion of the case bottom 1. The partition 10 is adapted to be disposed transversely of the bottom 1 and to ensure its retention, when desired, in a vertical position with respect to the bottom 1, channeled ribs 12 are secured to the inner sides of the intermediate portions of the side sections 3 and are adapted to be engaged over the adjacent marginal portions of said hinged partition 10. Thus, means will be provided for supporting the partition 10 in a vertical or upright position with respect to the shipping case and to divide the same into a plurality of compartments.

With a view towards providing further means for bracing and securing the end sections 7 and the partition 10 in their upright or substantially upright positions with "setting up" of the shipping case, substantially W-shaped guide members 13 are provided, one of such members being secured to the free marginal portion of each of the sections 7 and 10, preferably intermediate of the opposite ends of the same, as is clearly shown in the Figures 3 and 6; portions of these members 13 extending beyond the adjacent portions receiving the same, whereby to provide pins adapted to be engaged in openings 14 formed in ad-

jacent portions of the sections 5 when the same are arranged in their closed positions, as is shown in the Figures 1 and 3. Thus, means will be provided for effecting a brace as between the top sections 5 and the end sections 7 and likewise, means will be provided which will tend to retain the hinged top sections 5 in their closed positions with respect to the side and end sections 3 and 7 respectively. Also, it is to be understood that the looped portions of the members 13 will serve as effectual stops or abutments for the adjacent marginal portions of the top sections 5 as well as possible handles for facilitating moving of the cases when in their "set up" positions.

A substantially U-shaped bracket or loop 15 is fixedly secured to the lower portion of the partition 10, being disposed at substantially right angles thereto, as is shown in the Figures 2 and 3 and with folding or collapsing of the sections of the shipping case, it will be seen upon reference to the Figure 5 that the notched portions 16 of the top sections 5 will serve to permit the passage of portions of said bracket therethrough, thereby causing the free end of the bracket to be extended beyond the outermost folded section 5 in order that a tag, locking pin, or other device may be engaged therewith and that the folded sections will be securely retained in their relative folded or collapsed positions.

If desired, a suitable opening, slot or the like may be formed in the top sections 5 or other convenient parts of the shipping case whereby to permit the affixing or tying of a tag, or similar device to the shipping case.

To effect positive closure of that space occurring between the abutting or adjacent free extremities of the top sections, I may and preferably do provide laterally extending tongues generally indicated by the numerals 17, securing said tongues or folding the same upon the free marginal portions of said top sections in such a manner as to cause the same to be arranged in closed relationship with arrangement of the shipping case in its "set-up" position, as shown in the Figure 1. Thus, inasmuch as the laterally extending tongues are arranged in slightly different planes, overlapping engagement of the same will be permitted should the spacing as between the free marginal portions of the top sections 5 vary for any reason. Likewise, these laterally extending tongues will serve to reduce the space between the free portions of the top sections 5 and in consequence, prevent the live-stock contained within the cases from extending their legs, heads, or other parts of their bodies through such openings.

Manifestly, the construction shown is capable of considerable modification, and such

modification as is within the scope of my claims, I consider within the spirit of my invention.

I claim:—

5. 1. A shipping case comprising a bottom, vertically swinging sides and ends hinged to the opposite end and side portions of said bottom, top sections hingedly connected to the free extremities of said sides, and substantially W-shaped members secured to the free sides of said end sections and intermediately of the opposite sides thereof adapted to have the outer extremities of the opposite sides of the same engaged in openings formed in adjacent portions of said top sections and to have parts of the intermediate portions thereof abuttingly engaged with adjacent portions of said top sections.
10. 2. A shipping case comprising a bottom having the opposite sides thereof formed with upstanding flanges, end sections hingedly connected to the opposite ends of said bottom and vertically swingable with respect thereto, vertically swingable side sections hingedly connected to the marginal portions of said upstanding flanges, top sections hingedly connected to the free marginal portions of said side sections, and substantially W-shaped members secured to the free extremities of said end sections and intermediately of the opposite sides thereof adapted to have portions of the same engaged in openings formed in adjacent portions of said top sections and to have the intermediate portions thereof abuttingly engaged with adjacent portions of said top sections.
15. 3. A shipping case comprising a bottom having the opposite sides thereof formed with upstanding flanges, end sections hingedly connected to the opposite ends of said bottom and vertically swingable with respect to the same, vertically swinging side sections hingedly connected to the marginal portions of said upstanding flanges, top sections hingedly connected to the free marginal portions of said side sections, channeled ribs secured to the inner sides of

the opposite end portions of said side sections adapted to be engaged with adjacent portions of the end sections, at times, and substantially W-shaped members secured to the free sides of said end sections and intermediately of the opposite sides thereof adapted to have portions of the same engaged in openings formed in adjacent portions of said top sections and to have the intermediate portions thereof abuttingly engaged with adjacent portions of such top sections.

4. A shipping case comprising a sheet metal bottom having the opposite sides thereof formed with upstanding flanges, reticulated side sections hingedly connected to the free marginal portions of such flanges, reticulated end sections hingedly connected to the opposite end portions of said bottom, reticulated top sections hingedly connected to the free marginal portions of said side sections and adapted to be swung downwardly, at times, into engagement with the adjacent marginal portions of said end sections, channeled ribs secured to the inner sides of the opposite end portions of said side sections adapted to engage with the adjacent marginal portions of said end sections, a reticulated partition disposed transversely of the intermediate portion of said bottom and hingedly connected to the upper side thereof, other channeled ribs secured to the inner sides and intermediate portions of said side sections adapted to be engaged with the adjacent marginal portions of said partition, substantially W-shaped members fixedly connected to the free side portions of said end sections and said partition adapted to have the opposite extremities thereof engaged in openings formed in the adjacent portions of said top sections and the intermediate portions thereof to be abuttingly engaged with adjacent portions of said top sections, and laterally extending tongues carried upon the free marginal portions of said top sections.

In witness whereof I have hereunto set my hand.

OTTIS E. HARDESTY.
